IRRIGATION SOCK HOLDER

Elmer G. Heinrich, 824 E. 6th St., Goodland, Kans.

Filed Sept. 29, 1965, Ser. No. 87,222

Term of patent 14 years

(Cl. D91—3)

Fig.1.

Fig.2.

Fig.3.

Fig.4.

Fig.5.

FIG. 1 is a top plan view illustrating the irrigation sock holder, the irrigation gate valve and the flexible sock being shown in dot and dash lines;

FIG. 2 is a side elevational view of the sock holder;

FIG. 3 is a front elevational view thereof;

FIG. 4 is a rear elevational view thereof; and

FIG. 5 is a fragmentary cross-sectional view taken along line 5—5 of FIG. 1, a portion being broken away for clarity.

The irrigation gate valve and the flexible sock shown in dot and dash lines in FIGS. 1 and 2 are included for illustrative purposes only.

I claim:

The ornamental design for an irrigation sock holder, as shown and described.
